US00D424027S

United States Patent [19]

Shoda et al.

[11] Patent Number: Des. 424,027

[45] Date of Patent: ** May 2, 2000

[54] **HOUSING ADAPTED TO RELEASABLY RECEIVE A DEVICE BAY ELECTRONIC COMPONENT**

[75] Inventors: **Thomas Mamoru Shoda, Campbell; Livius Dumitru Chebeleu, Cupertino, both of Calif.**

[73] Assignee: **Palo Alto Design Group, Palo Alto, Calif.**

[**] Term: **14 Years**

[21] Appl. No.: **29/096,511**

[22] Filed: **Nov. 13, 1998**

[51] LOC (7) Cl. **13-03**

[52] U.S. Cl. **D13/184**

[58] Field of Search **D13/184; 361/600, 361/679, 683, 684, 685, 686**

[57] CLAIM

We claim the ornamental design for a housing, adapted to releasably receive a device bay electronic component as shown and described.

DESCRIPTION

FIG. 1 is a front elevation view of the housing showing our new invention;

FIG. 2 is a left elevation view thereof;

FIG. 3 is a top plan view thereof;

FIG. 4 is a right side elevation view thereof;

FIG. 5 is a back elevation thereof;

FIG. 6 is a bottom plan view thereof;

FIG. 7 is a perspective view of the preferred embodiment thereof showing the device closed; and,

FIG. 8 is a perspective view of the preferred embodiment thereof showing the device open.

The broken-line disclosure in the drawings is for illustrative purposes only and forms no part of the claimed design.
